UNITED STATES PATENT OFFICE.

FRANCIS A. FLEMING, OF CURWINSVILLE, PENNSYLVANIA.

DESIGN FOR A FENCE.

Specification forming part of Design No. 5,743, dated April 2, 1872.

To all whom it may concern:

Be it known that I, FRANCIS A. FLEMING, of Curwinstown, in the county of Clearfield and State of Pennsylvania, have invented a new and original Design for Fences; and I do hereby declare that the following is a full, clear, and exact description of the same, reference being had to the annexed drawing making a part of this specification, and to the letters and figures of reference marked thereon.

Figure 1 of the drawing is a representation of a perspective view of my designed fence.

My invention has relation to a novel design for ornamental fences, composed of wood and wire.

The nature of said design is clearly shown in the accompanying drawing, in which A A are the end posts of a panel; B B', horizontal bars connecting said posts; and D, the wires. The vertical parts of the wires pass through

holes bored at equal distances apart through the bars B B'. Above the bar B the wires are bent in an angular manner, so as to form the lattice-work D, having diamond-shaped spaces, embraced by the wires crossing each other. The upper termination of each wire is in a recess in the bar immediately behind the hole through which passes the next fourth wire. The ends of the lattice-work are completed as shown.

What I claim as my invention, and desire to secure by Letters Patent, is—

The design for a fence composed of wood and wire, substantially as shown and described.

In testimony that I claim the above I have hereunto subscribed my name in the presence of two witnesses.

FRANCIS A. FLEMING.
